UNITED STATES PATENT OFFICE.

PETER BARTOLETTI, OF BROWNSVILLE, PENNSYLVANIA.

ROTARY ENGINE.

No. 803,324.

Specification of Letters Patent.

Patented Oct. 31, 1905.

Application filed February 4, 1905. Serial No. 244,113.

To all whom it may concern:

Be it known that I, PETER BARTOLETTI, a subject of the King of Italy, and a resident of Brownsville, in the county of Fayette and 5 State of Pennsylvania, have invented a new and Improved Rotary Engine, of which the following is a full, clear, and exact description.

The object of the invention is to provide a 10 new and improved rotary engine which is simple and durable in construction, very effective in operation, and arranged to permit convenient and quick reversing and to utilize the motive agent to the fullest advantage.

15 The invention consists of novel features and parts and combinations of the same, as will be more fully described hereinafter and then pointed out in the claims.

A practical embodiment of the invention is 20 represented in the accompanying drawings, forming a part of this specification, in which similar characters of reference indicate corresponding parts in all the views.

Figure 1 is an end elevation of the improvement, one of the cylinder-heads being removed. Fig. 2 is a longitudinal sectional elevation of the improvement on the line 2 2 of 25 Fig. 1. Fig. 3 is a sectional plan view of the same on the line 3 3 of Fig. 1. Fig. 4 is an 30 inverted reduced plan view of the cylinder on the line 4 4 of Fig. 1; and Figs. 5 and 6 are face views of opposite ends of the cylinder, the corresponding piston-heads being removed.

The cylinder A of the engine is provided 35 with a base A' and cylinder-heads A² and A³, in which is journaled the main shaft B, connected at its outer end in the usual manner with other machinery to be driven from the rotary engine. On the shaft B, within the 40 cylinder A, is secured a piston C, having concentric rims C' and C² connected with each other by a central web portion C³, formed with spaced openings C⁴, in which extend radially-disposed wings D, forming piston-heads 45 against which presses the motive agent to turn the piston C either in a forward or reverse direction, as hereinafter more fully described.

The pivots D' of the wings D are journaled in the rims C' and C², and on the outer end of 50 each pivot D' is secured a shoe E, engaged by a cam device in the form of two oppositely-disposed cams F and F', secured to or formed on the corresponding cylinder-heads A² and A³, so that the wings D are turned from a 55 folding position or when in alinement with the web C³ into a right-angular position, so

that the side edges of the wings contact with correspondingly-shaped rings A⁴ and A⁵, secured to or forming part of the cylinder-heads A² and A³. The space between the rings A⁴ 60 and A⁵ forms the working chamber of the engine, so that the steam or other motive agent can act on the wings when in a right-angular position to turn the piston C either forwardly 65 in the direction of the arrow a' or backwardly in the reverse direction of the arrow a'. Into this working space extends an abutment made of two parts G and G', secured to or forming part of the rings A⁴ and A⁵, the parts being spaced from each other to permit the passage 70 of the web C³ and the wings D when the latter are in a closed position, as will be readily understood by reference to the top portion of Figs. 1 and 2.

The cam device consisting of the cam-rings 75 F and F' is so arranged that the wings D move into a closed position on approaching the abutment and are positively turned into a right-angular position by the said cam device and shoes E on leaving the abutment, the wings 80 being positively held in the right-angular position during their passage through the working space, it being expressly understood that the cams are so shaped relative to the abutment that the wings assume the position described, no matter in which direction the piston C is turned.

Into the working space of the cylinder open admission-ports a and b on opposite ends of the abutment G G' and the said ports open 90 into a steam-chest H, connected by a pipe I with a boiler or other suitable source of motive-agent supply. In the steam-chest H is mounted a slide-valve J for controlling the ports a and b in such a manner that when one 95 of the ports a or b is open the other is closed. For instance, as shown in the drawings, the port b is closed while the port a is open, so that the motive agent passes from the steam-chest H into the working space of the cylinder 100 on the right-hand side of the abutment G G' to turn the piston C in the direction of the arrow a'. The slide-valve J is manually controlled and for this purpose is engaged by one end of a screw-rod K, screwing in the end of 105 the steam-chest H and provided at its outer end with a handle K' under the control of the operator for the latter to turn the screw-rod K to shift the slide-valve J for opening one port and closing the other, as above described. 110

Exhaust-ports c and d extend through the ring A⁴ and the cylinder-head A² to the out-

side, the said ports being located a distance from the ends of the abutment, so that the steam acting on the wings while in a right-
angular position gives impulses to the piston
5 C to rotate the same, the steam finally ex-
hausting through the port c or d, according
to the direction in which the piston C is ro-
tating.

From the foregoing it will be seen that the
10 rotary engine is very simple and durable in
construction and is composed of comparatively
few parts not liable to easily get out of order.

For practical purposes it may be desirable
to make the rims C' and C² and their connect-
15 ing-webs C³ of parts separate from the body
portion of the piston C, as indicated in the
drawings; but this feature is not essential.

Having thus described my invention, I claim
as new and desire to secure by Letters Patent—

20 1. A rotary engine comprising a cylinder
having an abutment formed with a passage
extending from end to end of the abutment,
a piston mounted to turn concentrically in the
said cylinder and provided with spaced rims
25 forming with the cylinder-heads a working
chamber between which rims extends the said
abutment, the piston-web portion extending
between the rims passing through the said
abutment-passage, the said piston-web portion
30 having spaced openings, wings in the said
openings, mounted to turn in bearings in the
piston-rims, shoes secured on the outer pivots
of the wings, and oppositely-disposed cams
on the heads of the cylinder, engaged by the
35 said shoes, for turning the wings.

2. A rotary engine comprising a cylinder
having an abutment formed with a passage
extending from end to end of the abutment,
a piston mounted to turn concentrically in the
40 said cylinder and provided with spaced rims
between which extends the said abutment, the
piston - web portion extending between the
rims passing through the said abutment-pas-
sage, the said piston-web portion having spaced
45 openings, wings in the said openings, mounted
to turn in bearings on the piston, shoes se-
cured on the pivots of the wings, a fixed cam
in said cylinder, engaged by the said shoes,
for turning the wings, a steam-chest on the

50 said cylinder, connected with a steam-supply, the steam-chest being connected by admission-
ports with the cylinder on opposite ends of
the abutment, and a manually-controlled re-
versing-valve in the said steam-chest, over the
55 said ports.

3. A rotary engine, comprising a cylinder
having rings on the inner faces of its heads,
a piston having spaced and concentric rims
forming with the rings a working chamber,
the rims being connected by a central web 60
having a plurality of openings, wings pivoted
between the rims in the openings thereof and
provided with shoes on their pivots, an abut-
ment formed with a passage between which
extends the web of the rims, the abutment 65
extending between the rims of the piston,
and fixed cams for engaging the shoes on the
pivots of the wings.

4. A rotary engine, comprising a cylinder
having rings on its heads, abutments on the
70 rings, oppositely-disposed arms on the cylin-
der-heads outside of the rings, and a piston
mounted in the cylinder and comprising spaced
and concentric rims connected by a web hav-
ing a plurality of openings, and wings piv-
75 oted in the openings of the web and provided
on their outer pivots with shoes engaging the
said cams.

5. A rotary engine, comprising a cylinder
having rings on its heads, abutments of un-
80 equal length on the rings, cams on the cylin-
der-heads outside of the rings and terminating
opposite the abutments, and a piston mounted
in the cylinder and comprising spaced and
concentric rims connected by a web having a
85 plurality of openings and pivoted wings in
the openings of the web, the pivots of the
wings being mounted in the rims of the piston
and the outer pivots being provided with shoes
90 outside of the outer rim.

In testimony whereof I have signed my name
to this specification in the presence of two sub-
scribing witnesses.
